UNITED STATES PATENT OFFICE.

STANLEY W. HAYES, OF RICHMOND, INDIANA.

SWITCH-STAND.

1,312,691.

Specification of Letters Patent.

Patented Aug. 12, 1919.

Application filed January 19, 1918. Serial No. 212,756.

To all whom it may concern:

Be it known that I, STANLEY W. HAYES, a citizen of the United States, residing at Richmond, Wayne county, Indiana, have invented the following described new and useful Improvements in Switch-Stands.

The invention is an operating stand for derails, switch points or other track appliances. Its object is to produce a small operating stand of neat appearance, simple in form and extremely rugged in construction and economical to manufacture. The stand in its preferred form comprises five essential parts very easily put together.

15 In the accompanying drawings,

Figure 1 is a general perspective view of the improved stand;

Fig. 2 a top plan of the base of the stand with parts broken away;

20 Fig. 3 a transverse vertical cross-section through the axis of the stand;

Fig. 4 a top plan detail of the bell crank member; and

25 Fig. 5 a sectional detail of the operating handle.

The base of the stand is composed of two opposite flange members 1, provided with spike holes for attachment to the top surfaces of two adjacent railroad ties. These spike flanges are united by an upstanding arched roof portion 2, and a depressed floor portion 3 disposed below the level of the tie tops and adapted to occupy the space between them. Both the roof and floor portions are appropriately braced to the spike flanges by angle ribs, as shown, and the entire base is formed as a single or one-piece casting. The roof and floor portions are provided with shaft bearings in vertical alignment. The upper bearing is a drilled hole. The lower bearing may also be a drilled hole or a step bearing of any suitable type. It is preferred, however, to drill both bearings, which can be done in one operation. The target staff 4 inserted in these

50 bearings is held in place therein by the sleeve 5 of a crank arm member (separately shown in Fig. 4), which embraces and surrounds the staff between the bearings and in the space between the roof and floor portions. This sleeve 5 is set screwed to the target staff and therefore supports it vertically, if not otherwise supported, and also secures it against removal from the base, as will be evident. The crank arm member is essentially a bell crank. Its power arm is formed for

attachment to an operating handle 6, as presently described, and its other arm is formed for connection with the connecting rod 7 running to the switch point or other device to be operated. This lower arm is formed by an eye-bolt 8, threaded into a lug 9 on the crank sleeve, the said lug being eccentrically placed with respect to the axis of the crank, in order that the bolt may be screwed in and out as far as necessary to give the proper radius of throw. The end of the eye-bolt 8 is adapted for attachment to the connecting rod and will be observed to occupy the normal level of said rod, just below the level of the tie tops.

The power arm of the bell crank is formed by an integral web 10, extending laterally upward to the exterior of the space between roof and floor portions, where it carries the pivot 11 for the handle 6. The latter is bifurcated or slotted at its end and straddles the end of the web so as to obtain a secure operating bearing thereon. As shown in Fig. 5, the handle pivot 11 extends into both cheeks of the bifurcated end of the handle, and one of said cheeks is extended beyond the pivot to a position underneath the marginal flange 12 of the roof portion. This extended cheek, marked 13, serves as a latch to engage the slots or shoulders 14 and 15 of the roof flange 12, when the handle is depressed on its pivot, as clearly indicated in Fig. 1. When in such position, a padlock hole in the crank arm 10 is exposed above the handle, and a padlock hasp inserted therein will retain the cheek extension 13 in engagement with the slot 14 or 15 and thereby lock the switch stand against operation. When the padlock has been removed the arm can be swung upward to the position indicated in Fig. 3, and until the cheek extension 13 strikes the stop lug 16 formed on the operating arm, and in this position the switch stand may be operated as desired.

It will be observed that the target staff can be made of ordinary cold rolled steel, not requiring special machining, and that it is therefore cheaply produced; also that it is not weakened or reduced in cross section by any special formation adapting it to interlock with the crank sleeve, that a single set screw is sufficient for the purpose of locking and confining all of the parts in their assembled relation and that the bolt lug 9 being formed as an integral part of the web struc-

ture 10 of the crank sleeve on the same side as the operating handle, is thus in the best position for the transmission of the operating strain, affording a maximum strength 5 for a minimum for metal.

I claim:

1. A switch stand having a base comprising opposite spike flanges united by an up-standing roof portion and a depressed floor portion, said portions being provided with shaft bearings in vertical alinement, a target staff in said bearings, a crank sleeve secured thereon between the bearings, a lower arm on said crank sleeve adapted for connection to the operating track member, an upper arm thereon, and an operating handle
- 10
- 15

pivoted on said upper arm and adapted to swing vertically with reference to said crank sleeve.

2. The switch stand specified in claim 1, 20 having shoulders formed on its roof portion for interlocking with a part of said operating handle.

3. The switch stand specified in claim 1, 25 having a web structure on the crank sleeve serving as said upper arm and incorporating an eccentric lug in which the said lower arm is threaded.

In testimony whereof, I have signed this specification.

STANLEY W. HAYES.
